(57) **CLAIM**

The ornamental design for a display screen with an animated graphical user interface, as shown and described.

DESCRIPTION

FIG. 1 is a front view of a first image of a first embodiment of a display screen with an animated graphical user interface showing our new design;

FIG. 2 is a second image thereof;

FIG. 3 is a third image thereof;

FIG. 4 is a fourth image thereof;

FIG. 5 is a front view of a first image of a second embodiment of a display screen with an animated graphical user interface showing our new design;

FIG. 6 is a second image thereof;

FIG. 7 is a third image thereof; and,

FIG. 8 is a fourth image thereof.

The broken lines showing the display screen form no part of the claimed design. The remaining broken lines showing portions of the graphical user interface form no part of the claimed design.

The appearance of the animated graphical user interface sequentially transitions between the images shown in FIGS. 1-4 and FIGS. 5-8. The process or period in which one image transitions to another image forms no part of the claimed design.
